RESERVOIR PEN

Hiroshi Okada, Tokyo, Japan

Application April 4, 1934, Serial No. 719,024
In Japan August 30, 1933

2 Claims. (Cl. 120—47)

This invention relates to self-filling reservoir pens of the type comprising a piston adapted to be reciprocated within the pen barrel by means of a rod so that ink is drawn into the barrel on the outward stroke and passed to the other side of the piston during the instroke.

The objects of the invention are to provide an improved construction of the above-mentioned type and to provide a pen which is leak-proof.

According to this invention, the piston comprises an annulus or ring which is loosely mounted on an enlargement of the piston rod and capable of axial movement thereon between two stops, movement of the said annulus being effected by its engagement or contact with the wall of the barrel to allow ink to pass from one side of the annulus to the other.

The enlargement of the said piston rod may be cone-shaped to fit into a correspondingly shaped recess in the ink passage to the nib.

In order that the invention may be understood, it will now be described with reference to the accompanying drawing in which Figure 1 is a longitudinal section of one form of pen constructed in accordance with this invention; Figure 2 is a similar view to Figure 1, but showing the piston in another position; Figure 3 is a detail view; Figure 4 is a sectional elevation of another form of pen constructed in accordance with this invention; Figure 5 is a similar view to Figure 4 but showing the piston in a different position; Figure 6 is a detail view and Figure 7 is a perspective view of the piston ring.

Referring first to Figures 1 to 3 inclusive, the pen comprises a barrel *a* to which is screwed a pen cap *b* and a knob *c*. Inside the barrel *a* is fitted an india-rubber lining or bag *d*. *e* is a piston rod fitted in the knob *c*.

The other end of the rod *e* is provided with an enlargement *f* on which is loosely mounted an annulus or ring *g*. Axial movement of the said annulus is limited between the stops *h* and *j*. The end of the enlargement *f* is cone-shaped at *k* to fit into a correspondingly shaped recess *l* in the ink passage *m*.

In order to fill the pen, the nib is placed into the ink, and the knob *c* is unscrewed and the rod is gradually pulled out. By doing this, the annulus *g*, when it contacts with the lining *d* will move axially until it abuts against the stop *j*. The air inside the barrel will escape through the space *n* between the annulus *g* and enlargement *f*.

After the rod has been pulled up to its full extent, it is then pushed in and in doing so the annulus *g* moves axially until it abuts against

the stop *h* and closes the outlet *n*. On further movement, a vacuum is created in the barrel until the annulus *g* passes the lining *d* when the ink passes into the barrel.

When the knob *c* is screwed down, as seen in Figure 1, the cone *k* enters the recess *l* and seals the end passage *m* thus making the pen leak-proof.

Referring now to Figures 4 to 7, inclusive, the construction of the pen is similar to that illustrated in Figures 1 to 3, with the exception that the enlargement *f* of the rod is a different shape and the annulus *g* is tiltable, as well as being capable of axial movement. The enlargement *f* of the rod *e* is formed with a neck *p* of smaller diameter and on the neck is loosely mounted the annulus or ring *g'*.

As seen in Figure 7, the said annulus is formed with two diametrically opposite lugs *o*, *o*, adapted to coact with the stop *h* when the annulus travels up thereagainst and cause the annulus to tilt.

In order to fill this pen, the nib is placed in the ink, and the knob *c* is unscrewed and the rod is gradually pulled out. By doing this the annulus *g'* when it contacts with the lining *d* will move axially until it abuts against the head *k* and tilts as seen in Figure 4.

The air inside the barrel will escape between the annulus *g'* and the lining *d*. After the rod has been pulled up to its full extent, it is then pushed in and, in so doing the annulus *g'* resumes its normal position and moves axially until it abuts against the stop *h*. On further movement, a vacuum is created in the barrel until the annulus *g'* passes the lining *d* when the ink passes into the barrel.

What I claim is:—

1. A self-filling reservoir pen comprising a barrel having a restricted portion therein, a lining of india-rubber in said restricted portion, a screw cap carrying the nib at one end and a screw knob at the other and axially reciprocable means disposed inside said barrel, said means comprising a rod connected at one end to said knob and having at its other end an enlargement, a fixed flange and a stop spaced apart on said enlargement and an annulus loosely mounted on said enlargement and disposed between said flange and stop such that when the said rod is reciprocated in said barrel the annulus contacts with the lining in the restricted portion thereof there is relative movement between the annulus and the enlargement, the fixed flange serving as a control to regulate the

flow of air between the annulus and the enlargement.

2. A self-filling reservoir pen comprising a barrel having a restricted portion therein, a lining of india-rubber in said restricted portion, a screw cap carrying the nib at one end and a screw knob at the other and axially reciprocable means disposed inside said barrel, said means comprising a rod connected at one end to said knob and having at its other end an enlargement, a fixed flange and a stop spaced apart on said enlargement and an annulus loosely mount-

ed on said enlargement and disposed between said flange and stop, two diametrically opposite lugs on said annulus, such that when the said rod is reciprocated in said barrel and the annulus contacts with the lining in the restricted portion thereof there is relative movement between the annulus and the enlargement until the said lugs strike against the fixed flange and tilt the said annulus thus allowing air to pass between the annulus and the lining of the barrel.
